UNITED STATES PATENT OFFICE.

HERMAN STAHL AND AARON F. DICKEY, OF FRIEDENS, PENNSYLVANIA.

WIRE-STRETCHER.

SPECIFICATION forming part of Letters Patent No. 487,101, dated November 29, 1892.

Application filed June 25, 1892. Serial No. 437,990. (No model.)

To all whom it may concern:

Be it known that we, HERMAN STAHL and AARON F. DICKEY, of Friedens, in the county of Somerset and State of Pennsylvania, have 5 invented certain new and useful Improvements in Wire-Fence Stretchers; and we do hereby declare the following to be a full, clear, and exact description of the invention, such as will enable others skilled in the art to which 10 it pertains to make and use it, reference being had to the accompanying drawings, which form part of this specification.

Our invention relates to improvements in wire-fence stretchers; and it consists in the 15 particular construction, which will be fully described hereinafter, and particularly pointed out in the claims.

The object of our invention is to provide a 20 simple metallic wire-stretcher of the particular construction hereinafter shown and described that can be applied to the side of a post, the end of the wire placed in an opening therein, and then the same turned to position to tighten or slacken the wire by means 25 of a wrench.

In the accompanying drawings, Figure 1 is a 30 perspective view of a post with my invention applied thereto and showing a stay to prevent the post from turning. Fig. 2 is an enlarged detached perspective of the stretcher.

A indicates a fence - post, and B a stay which is applied at one side of the post to prevent the same from turning under the tension of the wires.

C indicates a stretcher, which consists of a 35 central round hub portion D, which is provided with an opening E, which extends therein radially for the reception of the end of the wire which is to be secured and wound thereto. The inner face of this round portion is provided with ratchet-teeth F, which are forced into the post, as hereinafter described, and prevent the hub from revolving under the tension of the wire.

We show ratchet-teeth F' upon the periphery of the stretcher, which, as will be readily understood, form shoulders or abutments with the post with which they engage when the face of the stretcher is forced therein, as described, thus making the holding of the stretcher against turning all the more secure. However, these may be omitted, as will be 45 readily understood.

The outer end G of the hub portion is made 50 angular, as shown, preferably hexagonal, to receive an ordinary wrench, by means of which the stretcher can be turned and the wire thus tightened.

The stretcher is provided with a central longitudinal opening H, through which a 60 large screw I passes into the post and by means of which the stretcher is held in place and the teeth F forced into the post. This screw is also provided with a square head, so that it can be turned by a wrench, and is 65 provided with a "gimlet-screw" at its inner end, so that it can be started by driving and then turned to position.

In operation the stretcher is turned by a wrench until the desired tension is acquired 70 and held in this tightened position while another wrench is applied to the screw, and thereby the teeth of the stretcher forced into the post to prevent it from turning.

From the above description it will be seen 75 that we have produced a very simple and cheap stretcher, which can be quickly and readily applied to posts and then the end of the wire inserted into the opening in the periphery of the hub portion thereof and 80 twisted or wrapped around it, and thus stretched to any desired degree, the stretcher being held against rotation by forcing the teeth F into the post by the screw or bolt I.

Having thus described our invention, what 85 we claim, and desire to secure by Letters Patent, is—

1. A wire-stretcher comprising a casting having a longitudinal opening and teeth upon its inner end or face, adapted to engage a post, 90 an outwardly-projecting hub portion around which the wire is wrapped, and a holding and clamping screw or bolt passing through the said stretcher into the post.

2. A wire-stretcher comprising a casting 95 having a longitudinal opening, teeth upon the inner end or face, adapted to engage a post, a hub portion extending outward from the said toothed end and having its outer end made angular, for the purpose described, 100 and a clamping-screw passing through the longitudinal opening into a post.

In testimony whereof we affix our signatures in presence of two witnesses.

HERMAN STAHL.
AARON F. DICKEY.
